UNITED STATES PATENT OFFICE.

ROBERT N. WHITE, JR., OF GREENVILLE, TEXAS.

ATTACHMENT FOR CASH-REGISTERS.

1,306,240.

Specification of Letters Patent. Patented June 10, 1919.

Application filed November 9, 1918. Serial No. 261,906.

To all whom it may concern:

Be it known that I, ROBERT N. WHITE, Jr., a citizen of the United States, residing at Greenville, in the county of Hunt and State 5 of Texas, have invented a new and useful Attachment for Cash-Registers, of which the following is a specification.

This invention relates to an attachment for cash registers whereby losses due to forgetfulness or dishonesty of clerks making 10 sales, are materially reduced.

In some stores it has been the practice to have the salesman wrap the purchases on a counter, receive the money therefor and then 15 enter the sales and deposit the cash in the register. Very often the latter transaction is overlooked by mistake, forgetfulness, or dishonesty, with the result that leakages occur that often amount to considerable sums.

20 It is an object of the present invention to combine with an ordinary cash register, an attachment whereby it is not possible to remove paper for wrapping purposes until after the drawer of the cash register has 25 been opened by the salesman recording the amount of the purchase, the location of the wrapping paper close to the register tending to hold the customer in front of the register where the amount of the sale will be 30 visible in the register and the likelihood of a false record reduced to the minimum.

It is also designed, by utilizing means for preventing the removal of wrapping paper unless the drawer is open, to compel the operation of the register every time a sale is 35 made.

With the foregoing and other objects in view, which will appear as the description proceeds, the invention consists of certain 40 novel details of construction and combinations of parts which will be hereinafter more fully described and pointed out in the claims, it being understood that various changes may be made in the construction

45 and arrangement of the parts without departing from the spirit or sacrificing any of the advantages of the invention as set forth in the appended claims.

In the accompanying drawings the preferred form of the invention has been shown.

In said drawings—

Figure 1 is a front elevation of a cash register having the present improvements combined therewith, the paper rack being 55 shown in section and the attachment in position to prevent unrolling of the paper.

Fig. 2 is a side elevation of the structure shown in Fig. 1, the positions of the parts, when the drawer of the cash register is open, being indicated by dotted lines. 60

Fig. 3 is a perspective view of a portion of the drawer and the crank connected thereto.

Fig. 4 is a side elevation of a portion of the attachment and drawer and showing the relative positions of the parts when the 65 drawer is half-way out.

Referring to the figures by characters of reference, 1 designates a wrapping counter on which is mounted a cash register 2 adjacent which is a rack 3 supporting superposed 70 rolls 4 of wrapping paper. The attachment constituting the present invention includes an upstanding frame 5 or the like secured to the counter between the rolls 4 and the cash register, and in this frame is 75 journaled a shaft 6 one end of which extends between two of the rolls 4 while its other end has a crank arm 7. This arm 7 is close to one side of the path of movement of the drawer 2' of the cash register and is 80 connected to one side of the drawer, at the front thereof, by a link 8. Secured to that end of the shaft 6 remote from the crank 7 is a guard rod 9 so proportioned that, when it is in a vertical position, it will extend in 85 front of and close to all of the rolls of paper 4 and prevent sheets from being torn therefrom. When it is in a horizontal position, however, it will lie between the levels of two adjoining rolls 4 and allow paper to be 90 unrolled from any of said rolls.

When the drawer 2' is closed the rod 9 is in vertical position. When the drawer is opened, the link 8 thrusts against the crank 7, swings thereover, as shown in Fig. 4, and 95 then pulls on the crank until the rod 9 is brought to horizontal position. In closing the drawer the foregoing operation is reversed and the rod 9 brought to vertical position. 100

What is claimed is:—

1. An attachment for cash registers, including a paper holding rack, a shaft extending therethrough, means normally positioned to prevent removal of paper from the rack, said means being operated by the shaft, and means operatively connected to the shaft for attachment to the drawer of a cash register to operate the shaft and release the paper when the drawer is opened. 105

2. The combination with a cash register, and a paper holding rack adjacent thereto, 110

of a shaft, a guard member at one end of the shaft and normally positioned to prevent removal of the paper, a crank arm at the other end of the shaft, and a connection between 5 the crank arm and a movable part of the cash register for actuating the shaft and moving the guard member to release the paper when the cash register is operated.

3. The combination with a cash register, 10 a drawer, and a paper holding rack adjacent thereto, of a shaft, a guard member at one end thereof and normally positioned to

prevent removal of the paper from the rack, a crank arm at the other end of the shaft, a link connecting the crank arm to the drawer 15 of the cash register.

In testimony that I claim the foregoing as my own, I have hereto affixed my signature in the presence of two witnesses.

ROBERT N. WHITE, JR.
